UNITED STATES PATENT OFFICE

JOHN R. GRUETTER, OF CLEVELAND, OHIO, ASSIGNOR TO THE LIQUID CARBONIC CORPORATION, OF CHICAGO, ILLINOIS, A CORPORATION OF DELAWARE

BOTTLE BRUSHING APPARATUS

Application filed September 14, 1929. Serial No. 392,662.

This invention relates to apparatus for cleaning bottles, and more particularly to the mechanism for brushing the exteriors of the bottles; as, for instance, during their intermittent advance through an apparatus wherein the bottles are subjected to various cleaning operations in addition to the brushing operation.

The invention is shown herein as particularly applicable to a bottle cleaning apparatus wherein the bottles are mounted in transverse series of bottle supports and wherein each transverse series of bottle supports may constitute an element of an endless conveyor by which the bottles and their supports are advanced intermittently through an apparatus wherein the bottles are subjected to additional cleaning treatments while in transit.

The general purpose and object of the invention herein is to provide, for bottle cleaning mechanism, simple and effective means for thoroughly brushing the exteriors of the bottles while in transit. Further and more limited objects of the invention are to improve the construction and mode of operation of such brushing mechanism.

In the drawings forming part hereof, Fig. 1 represents a transverse sectional view through part of a bottle cleaning apparatus in which my invention is embodied, the bottle-lifting and lowering spindles, the bottle supporting frame, and the brushing mechanism being shown in elevation; Fig. 2 is a plan view and Fig. 3 is a side elevation of the assembly shown in Fig. 1; Fig. 4 a detail in elevation of the spindle cross head and the means for raising and lowering the same; Fig. 5 a detail in vertical section through the brushing mechanism and part of a bottle-supporting frame; Fig. 6 a detail in section through the brushing mechanism, the bottle supporting frame being shown in elevation and in its elevated position, the view showing the positions of the parts when a series of bottles is projected into the lower portion of the brushing mechanism; Fig. 7 is a view, similar to Fig. 6, and showing the positions of the parts when the bottles are in their uppermost positions with reference to the brushing mechanism; Fig. 8 a detail in sec-

tion through one of the brushes which operates upon the bottoms of the bottles; Fig. 9 a bottom plan view of one of such brushes; and Fig. 10 a detail in section through one of the swinging links by which the brush frames are suspended.

Describing the parts by reference characters, 1 denotes a pair of channeled tracks on which transverse bottle supporting frames 2 are mounted by rollers 3. In a type of bottle cleaner which is in extensive use, the frames 2 are flexibly connected in such manner as to form a continuous conveyor, which conveyor is moved intermittently along the tracks 1. Each frame 2 contains a transverse series of bottle supports 4, each support being shown as an open-top receptacle having a substantially frusto-conical bottom 4^a for supporting a bottle by engagement with the bulging shoulder thereof, in Figs. 1, 5, 6 and 7 the bottles being shown at 5 and each having its neck 5^a projected through the opening in the seating portion 4^a of the support.

Mounted in any suitable manner above the rails 2 is the brushing apparatus, the said apparatus comprising a pair of transversely extending upper brushes, a pair of transversely extending lower brushes which are movable toward and from each other, means for reciprocating the said brushes, and a series of bottle-bottom brushes, with means for rotating the latter.

6 denotes a framework extending transversely of the apparatus, said framework having a pair of depending brackets 7 at each end thereof, each of the brackets at each end of the framework being provided with a bearing sleeve 8, which sleeves support the ends of a shaft 9, driven by a gear 10 thereon meshing with a pinion 11 on a short shaft 12 which in turn is driven by a pulley 13. The outer end of the shaft 12 is supported by a bearing sleeve 12^a on an upwardly extending bracket 14 mounted on a post 15 and which bracket forms part of the support for the framework 6.

The shaft 9 is provided, intermediate its ends, with a beveled pinion 16 meshing with a beveled gear 17 on the bottom of a shaft

18 which carries at its upper end a master gear 19, the said master gear being mounted in the offset central portion of a gear box 20 and meshing with the central gear of a 5 transverse series of gears 21 in said box, each of which gears 21 is secured to a hollow spindle 22 by means of a key 22^a, which hollow spindle is in turn mounted within a bushing 23. Each hollow spindle 22 is provided with an angular bore for the reception 10 of an angular reciprocable spindle 24, each spindle 24 having secured to its lower end an inverted cup 25 provided at its bottom with downwardly and outwardly extending 15 fingers 26 and having radial ribs 28 projecting thereinto from the cylindrical wall thereof. Within each cup 25 there is reciprocably mounted a brush comprising a base 27 having radial slots for the reception of 20 the ribs 28. Secured to the base are the bristles 29 of the brush; and the brush is reciprocably mounted in the cup by means of studs 30 extending through openings in the 25 upwardly presented cup bottom. Each cup is secured to a spindle 24, as by means of a pin 31 extending through the hub 32 of the cup and the lower end of the spindle.

33 denotes a pair of upper brush frames each carrying the bristles 34, the said brush frames extending transversely of the apparatus and being spaced apart a distance which will enable the brushes to operate efficiently on the outer surfaces of the bottles 5. Each brush frame is suspended from the 35 framework 6 by means of a pair of links 35 and 36, each mounted at its upper end on a pivot pin 37. Each of the links 35 and 36 is pivotally connected at its lower end to a frame 33, as by pivot pins 38. As it is desirable to cushion the to-and-fro movement of the brush frames at the end of each stroke, the following construction is employed in the connections for reciprocating the frames through the links 36:—39 denotes a crank 40 shaft which is journaled in the brackets 7 at the end of the framework 6 which is opposite the pulley 13 and which has adjacent one end thereof of a beveled gear 40 meshing with a beveled pinion 41 on the shaft 9. The shaft 45 39 is provided at one end with a crank 42 having a crank pin 42^a while the beveled gear 40 at the opposite end of the shaft is provided with a crank pin 43. 44 denotes connecting rods extending from the crank pins 42^a and 43, respectively, and each projecting through an aperture 45 provided intermediate the ends of each of the links 36. Each rod 44 is mounted in a small hub 46 located within each aperture 45, the said 50 hubs being pivotally mounted in the apertures 45 by means of trunnions 47—see Figs. 7 and 10. A coiled spring 48 is interposed between one side of the hub 46 and an adjustable stop 49 on each rod 44, while a similar coiled spring 50 is interposed between the

opposite side of each hub 46 and adjustable nuts 51 on the outer end of each rod 44. It will be obvious that, as the shaft 39 is rotated, the thrust of the rods 44 in either direction will be cushioned against the arms 36 by the 70 springs 48 and 50, thus relieving the brush frames of jar at the end of each stroke—when their movement is reversed.

Secured to each of the rails 1 and projecting upwardly therefrom is a bracket 52. Each of these brackets has pivoted thereon a gear segments 53, and one of these segments is provided with an operating lever arm 54. The outer end of the arm 54 is connected to a rod 55 which is slidably mounted in a sleeve 56 pivotally connected to the top of a link 56 pivoted at its lower end to a lever arm 57 having one end secured to one end of a rock shaft 58 while its other end is connected by a link 59 to one end of a cross head 60 which carries a transverse series of lifting rods 61 and which is slidably mounted on guide rails 60^a. Each of the rods 61 has mounted thereon a bottle engaging spindle 61^a having a mouth engaging portion 61^b, the spindle being rotatably mounted on a ball 61^c at the bottom of a sleeve formed in the top of said rod. The opposite end of the cross head is connected by a link 59^a and a lever arm 57^a to the opposite end of the rock shaft 58.

Each of the gear segments 53 is provided with an upwardly extending frame 53^a each having at its upper end a pair of vertically extending rollers 53^b.

62 denotes a pair of lower brush frames, each having bristles 63 and each such frame being pivotally suspended from the ends of the main upper brush frames 33 by links 64, each link being pivoted at its upper end on a stud or pin 65 carried by the corresponding end of the upper brush frame and each of the lower brush frames being in turn mounted in the lower ends of the links 64 by means of rods 66. These rods extend between the rollers 53^b so that, when the arm 54 is rocked through the movement of the lever 57, this movement will rock the brush frames 62 toward or from each other, depending upon the direction of movement of the rod 55. Normally, the lower brushes will be in the 100 positions shown in Figs. 3, 5 and 6, with the lower ends of the frames diverging outwardly so as to provide a downwardly divergent space therebetween for the reception of the bottles 5 and the cups 25. In order not to close this space until the bottles shall have been lifted to the desired extent, there is a lost-motion connection between the lever 57 and the rod 55 which rocks the lower brushes. This lost motion connection is obtained by the sleeve 56^a and a stop 55^a on the rod, whereby the head 60 with its spindle rods 61 will necessarily have to be elevated until the sleeve and the stop contact before the lower brushes can be rocked toward each other,

which will occur after the bottles have been lifted the desired distance above their supports 4 by the spindle rods.

A spring 67 which is connected to the arm 54 and to a fixed part of the structure, serves to rock the said arm and to move the bottoms of the lower brushes outwardly as soon as the rod 55 moves downwardly.

In Figs. 5 and 6, the brushes are shown in 10 the positions which they occupy immediately before a transverse series of bottles is elevated between the upper brush frames 33 by the spindle rods, while Fig. 7 shows the positions of the brushes after the bottles have 15 been raised to bring their bottoms between the upper brushes, and when the the bottles are in their most elevated position. From these views, it will be evident that when the bottoms of the bottles engage the brushes in 20 the cups 25, the brushes serve to cushion the impact of the bottle bottoms and, because the brush spindles are rotating rapidly, there will be some slippage between the brushes proper and the bottle bottoms, with the result that the bottoms of the bottles will be 25 cleaned by such brushes. As the bottles move upwardly, their sides are operated upon by the upper brushes while the lower brushes are swung inwardly to contact with the shoulders and necks of the bottles. During this 30 operation, the brushes on each side are reciprocated in reverse directions by the crank shaft 39 and the crank connections between said shaft and the arms or links 36. Pipes 35 68 extend longitudinally of and above the brushes and serve to supply jets of water to the brushes and the bottles during the brushing operation.

By virtue of the construction and arrangement of parts shown and described herein, a transverse series of bottles may be quickly and most effectively brushed and cleaned; the life of the brushing mechanism is prolonged through the yielding drive afforded 45 between the crank shaft and the swinging arms 36; and the danger of breakage to the bottles is reduced to a minimum.

Having thus described my invention, what I claim is:

50 1. In a bottle cleaning apparatus, the combination of a series of bottle supports, a pair of opposed spaced upper reciprocable brushes arranged above said bottle supports, a pair of brushes movably supported below the first brushes, a series of vertically reciprocable bottle-bottom brushes arranged between the first mentioned brushes and means for rotating such bottle-bottom brushes, means for lifting the bottles from their supports and for elevating the same between the first and second pairs of brushes with the bottoms of the bottles in engagement with the bottle-bottom brushes and for thereafter returning the bottles to their supports, means 55 operative through the lifting of the said bot-

60 tles for moving the second pair of brushes inwardly toward each other, thereby to bring them into engagement with the shoulders and necks of the bottles, means for reciprocating the first and second pairs of brushes, and means operative by the return of the bottles to their supports for separating the second pair of brushes.

2. In a bottle cleaning apparatus, the combination of a series of bottle supports, a pair 65 of opposed spaced upper reciprocable brushes arranged above said bottle supports, a pair of brushes below the first mentioned brushes and pivotally supported from said first-mentioned brushes in separated relation, a series of vertically reciprocable bottle-bottom brushes arranged between the first pair 70 of brushes and means for rotating such bottle-bottom brushes, means for lifting the bottles from their supports and for elevating the same between the first and second pairs of brushes with the bottoms of the bottles in engagement with the bottle-bottom brushes and for thereafter returning them to their supports, means operative through the lifting of the said bottles for rocking the second pair of brushes about their supports toward each other and into engagement with the shoulders and necks of the bottles, means 75 for reciprocating the first and second pairs of brushes, and means operative by the return of the bottles to their supports for rocking the second pair of brushes about their pivots away from each other thereby to withdraw said brushes from engagement with the necks and shoulders of the bottles and to hold said brushes in separated relation.

3. In a bottle cleaning apparatus, the combination of a series of bottle supports each adapted to support a bottle mouth-downward thereon, a pair of opposed reciprocable brushes above the said bottle supports, a series of bottle-bottom brushes arranged between the first-mentioned brushes, vertically movable supports for said bottle-bottom brushes, means for rotating said supports, and vertically movable means for connecting the said brushes with their respective supports for vertical movement with respect thereto, means for lifting the bottles from their supports and for elevating the same between the first mentioned brushes with the bottoms of the bottles in engagement with the bottle-bottom brushes, means for reciprocating the first mentioned brushes, and means for lowering the bottles to their supports at the conclusion of the brushing operation.

4. In a bottle cleaning apparatus, the combination of a series of bottle supports, a pair of opposed upper reciprocable brushes above said bottle supports, a pair of brushes arranged below the first brushes and pivotally supported therefrom, means for lifting the bottles from said supports and for elevat-

ing the same between the said brushes and for thereafter returning them to said supports, and means operative through the lifting of the said bottles for moving the lower brushes toward each other thereby to bring them into engagement with the shoulders and necks of the bottles, means for reciprocating the said brushes, and means operative by the return of the bottles to their supports 10 for separating the lower brushes.

5. In a bottle cleaning apparatus, the combination of a series of bottle supports, a pair of opposed upper reciprocable brushes above said bottle supports, a pair of brushes 15 pivotally supported below the first brushes, means for lifting the bottles from their supports and for elevating the same between the said brushes and for thereafter returning them to said supports, and means operative by the lifting of the bottles between the brushes for rocking the lower brushes about their pivotal supports thereby to bring such brushes into engagement with the shoulders and necks of the bottles projected therebetween, means for reciprocating the said 20 brushes, and means operative by the return of the bottles to their supports for rocking the lower brushes about their pivotal supports thereby to bring such brushes out of engagement with the shoulders and necks 25 of the bottles.

6. In a bottle cleaning apparatus, the combination of a series of bottle supports, a pair of opposed upper reciprocable brushes above 30 said bottle supports, a pair of brushes pivotally supported below the first brushes, means for lifting the said bottles from their supports and for elevating the same between the said brushes and for thereafter 35 returning them to said supports, rocking means for said lower brushes normally holding them with their brushing surfaces diverging downwardly, and means whereby the upward movement of such bottle lifting 40 means will rock the lower brushes thereby to move them into engagement with the bottles inserted therebetween and the downward movement of said bottle lifting means will 45 rock the said brushes in the reverse direction.

50 7. In a bottle cleaning apparatus, the combination of a series of bottle supports, a pair of brushes above said supports, a brush movably mounted below each of the first mentioned brushes, means for moving the said lower brushes toward and from each other, said means normally holding the brushes in separated relation, means for lifting the bottles from their supports and for moving them upwardly between the said brushes and for thereafter lowering the said bottles upon their supports, connections between the bottle-raising-and-lowering means and the brush-moving means whereby the lower brushes will be moved toward each other 55 when the bottles shall have been raised a

predetermined distance from their supports and will be separated by the downward movement of the lifting means, and means for reciprocating the said brushes.

8. In a bottle cleaning apparatus, the combination of a series of bottle supports, a pair of brushes movably mounted above said supports, means for lifting the bottles from their supports and for moving them upwardly between said brushes and for thereafter 60 returning them to their supports, connections between such bottle-raising-and-lowering means and the brushes for moving the brushes toward each other as the bottles move upwardly, means for separating the brushes when the bottles move downwardly, and means for reciprocating said brushes in a plane transverse to their movement toward and away from each other.

9. In a bottle cleaning apparatus, the combination of a series of bottle supports each adapted to support a bottle mouth-downward thereon, brushes above the said bottle supports adapted to operate on the sides of 65 bottles, a series of bottle-bottom brushes comprising each an inverted cup, a brush reciprocal in said cup and a reciprocal spindle connected with said cup, means for rotating said spindles, means for lifting bottles from their supports and elevating the 70 same between the first mentioned brushes with the bottoms of the bottles in engagement with the bottle-bottom brushes, and means for lowering the bottles to their supports at the conclusion of the brushing operation.

10. A bottle-bottom brush comprising a cup adapted to engage the bottom of a bottle, means for rotating the same, and a brush proper reciprocably mounted in said cup and having a driving connection therewith.

11. A bottle-bottom brush comprising a cup adapted to engage the bottom of a bottle with means for rotating the same, and a brush proper within said cup, the said brush comprising a base reciprocably mounted in said cup, the interior of the said cup and the said base having interengaging recesses and projections whereby the said brush is driven by the said cup.

12. A bottle-bottom brush comprising a cup having fingers sloping outwardly from the rim thereof and means for rotating said cup, and a brush proper having a base provided with one or more pins projecting through the bottom of the cup, the cup having a plurality of radial ribs and the brush base having slots for said ribs.

13. In bottle cleaning apparatus, the combination of a series of bottle supports, a pair of brushes located above said supports, a brush pivotally supported below each of the first mentioned brushes, a vertically reciprocal cross head, lifting rods carried by said cross head and adapted, when the cross head

is elevated, to lift the bottles from their supports, means for raising and lowering the said cross head, interengaging means for simultaneously rocking the lower brushes about 5 their respective pivots, a connection between the first mentioned means and the second mentioned means for rocking the lower brushes inwardly toward each other about their pivots when the bottles shall have been raised a pre-

determined distance by the lifting rods, and means for rocking the brushes outwardly about their supports through the second mentioned means as the bottles are lowered toward their supports.

In testimony whereof, I hereunto affix my signature.

JOHN R. GRUETTER.
